JEULEOS GAMBLLEE, OF TENAFLY, NEW JERSEY.

PLUMB-BOB.

1,076,569.

Specification of Letters Patent.

Patented Oct. 21, 1913.

Application filed May 26, 1913. Serial No. 769,862.

To all whom it may concern:

Be it known that I, JEULEOS GAMBLLEE, a citizen of the United States, and a resident of Tenafly, in the county of Bergen and 5 State of New Jersey, have invented a new and Improved Plumb-Bob, of which the following is a full, clear, and exact description.

This invention relates to mechanics' implements, and has particular reference to 10 the novel construction of plumb bobs.

Among the objects of the invention is to provide a plumb bob, the body of which is adapted to house the cord by which the bob is suspended while in use.

15 Another object of the invention is to improve the construction whereby in a simple and reliable manner the drum or spindle on which the cord is wound when housed within the device may be manipulated either to 20 withdraw the cord, to return the cord into the bob, or to lock it at any desired length.

The foregoing and other objects of the invention will hereinafter be more fully described and claimed and illustrated in the 25 drawings forming a part of this specification in which like characters of reference indicate corresponding parts in all the views, and in which—

Figure 1 is a vertical sectional view indicating the construction of this device in a 30 preferred embodiment; Fig. 2 is a transverse section on the line 2—2 of Fig. 1; and Fig. 3 is a side view, looking toward the right in Fig. 1, of certain parts removed 35 from the interior of the shell of the device.

The several parts of this device may be made of any suitable materials, and the relative sizes and proportions of the same may be varied to a considerable extent without 40 departing from the spirit of the invention hereinafter more fully set forth and specifically claimed.

In Fig. 1 I show a plumb bob of well known configuration and including a point 45 10 having an upwardly projecting internally threaded flange 11 and a collar 12 having a downwardly projecting externally threaded flange 13 upon which the point flange 11 is adapted to fit. The collar 12 50 has an upwardly projecting neck 14.

Within the interior of the bob or the casting composed of the flanged portions of the point and collar is a shell 15 of substantially tubular or hollow cylindrical formation, the axis of which is coincident with the vertical axis of the plumb bob. The lower

end of the shell 15 is fitted substantially snugly within the flange 13 of the collar and is prevented from rotation therein by means of studs 16 projecting outwardly beyond 60 said shell and entering notches 17 formed in the lower edge of the flange 13. A drum or shaft 18 is journaled transversely in said shell 15 at substantially its center, and the lower or inner end of the plumb bob cord 19 is fixed to said shaft. The upper portion of the shell 15 is of less diameter than the lower portion, and a pinion 20 is fixed to 65 said shaft on the outer side of the portion of the shell or between the shell and the flange 13 of the bob collar. A yoke 21 formed of flat sheet metal and formed into a substantially U-shaped structure is introduced into the interior of the shell, as shown in Figs. 1 and 2, and the shaft 18 is passed 70 therethrough, maintaining the yoke in the position indicated. The purpose of this yoke, among others, is to guard the cord 19 and prevent it from becoming entangled in the bearings in the shell. 75

As a suitable means to control the operation of the shaft 18 and therefore the length or position of the cord, I provide a crown gear 22 fitted loosely upon the upper end 80 of the shell and having teeth 23 meshing with the teeth of the pinion 20. A hollow shank 24 extends upwardly from the crown gear with its axis coincident with the axis of the interior device and having a central bore 25 through which the cord 19 extends 85 outwardly, terminating in a ring or hanger 26. When the crown gear is free to rotate, a pull upon the hanger 26 will draw the cord out of the bob, unwinding the same 90 from the shaft 18. During such operation 95 of the cord, the crown gear will be rotated by the pinion 20. I provide a lock nut 27 adjustably mounted upon the threaded portion 24' of the shank and adapted to impinge against the upper portion of the neck 100 14. This action of the lock nut locks the crown gear from rotation and hence prevents the rotation of the pinion and shaft. It will follow, therefore, that when the cord 105 is drawn out as far as desired, a slight turn of the lock nut will lock the operating parts of the device and will maintain the cord at the length indicated. When it is desired, however, to return the cord within the casting, the lock nut 27 is loosened by a slight 110 reverse movement, and then by rotating the crown gear as by operation upon the finger

piece 28, the crown gear through its engagement with the pinion 20 will wind up the string within the casing. The gear 22 being so much larger than the pinion 20, a 5 comparatively few rotations of the finger piece and shank 24 to which it is connected will suffice to wind up the maximum amount of cord. The finger piece 28 is preferably keyed to the upper end of the shank by 10 means of a set screw 29 for convenience of assembling or disassembling.

Having thus described my invention, I claim as new and desire to secure by Letters Patent:-

15. 1. In a plumb bob, the combination of a two-part casing, a shell within the casing, a shaft journaled in the shell, a cord connected at one end to the shaft and wound thereupon, and means to control the winding and unwinding actions of the cord with respect to the shaft, said controlling means comprising a crown gear, a pinion in mesh with the gear, and means extending upwardly from the crown gear to control the 20 rotation thereof from the outside.
2. In a plumb bob, the combination of a hollow casing, a shell within the casing, a shaft journaled transversely of and in the shell, a pinion connected to the shaft, a gear 25 embracing the upper end of the shell and meshing with said pinion, a shank having a central bore extending upwardly from the said gear to the outside of the casing, a cord connected at its inner end to the shaft and

extending thence outwardly through said shank, and means coöperating with the upper end of the shell to control the rotation of the shank and shaft.

3. In a plumb bob, the combination of a two-part casing having a detachable threaded connection, a shell fitted within the casing and provided with means to prevent rotation thereof within the casing, a substantially U-shaped yoke within the shell, a shaft journaled transversely in said shell and yoke, a pinion connected to the shaft, a crown gear rotatably fitted upon the upper end of the shell and meshing with said pinion, a cord connected at one end to the shaft and maintained in position thereon by said yoke, a screw threaded shank extending upwardly and axially from said crown gear and having a central bore through which said cord is extended, means at the upper end of the shank to rotate the same in one direction to wind up the cord, and means adjustable along the threaded portion of the shank and adapted to coöperate with the shell to prevent the rotation of the shank and crown gear, substantially as set forth.

In testimony whereof I have signed my name to this specification in the presence of two subscribing witnesses.

JEULEOS GAMBLIEE.
